UNITED STATES PATENT OFFICE.

JOHN P. ODGERS, OF PHILADELPHIA, PENNSYLVANIA, ASSIGNOR TO THE
A. M. COLLINS MANUFACTURING COMPANY, OF SAME PLACE.

DESIGN FOR A PHOTOGRAPHIC-CARD MOUNT.

SPECIFICATION forming part of Design No. 23,518, dated July 31, 1894.

Application filed July 9, 1894. Serial No. 517,015. Term of patent 7 years.

To all whom it may concern:

Be it known that I, JOHN P. ODGERS, a citizen of the United States, residing in Philadelphia, Pennsylvania, have invented a new and original Design for a Photographic-Card Mount, of which the following is a specification.

My design is fully shown in the accompanying drawings, in which—
10 Figure 1, represents a face view of the card mount; and Fig. 2, an enlarged sectional view of the same.

The mount is rectangular in outline and has a central circular medallion A bordered by an annular groove or depression a which is surrounded by a raised rib or bead b. The 15 face of the medallion A is plain, but the face of the mount outside of the rib b is grained

or roughened and in each corner of the mount is an ornament d consisting of a bunch of 20 twigs.

The essential feature of the design is the central circular medallion having a plain surface and contained within a mount of rectangular outline having its surface, beyond the 25 medallion, grained or roughened.

I claim—

The design for a photographic card mount, substantially as shown and described.

In testimony whereof I have signed my 3c name to this specification in the presence of two subscribing witnesses.

JOHN P. ODGERS.
